(57) **CLAIM**

The ornamental design for a perineal rehabilitation controller, as shown and described.

DESCRIPTION

FIG. 1 is a perspective view of a perineal rehabilitation controller;

FIG. 2 is a front side view thereof;

FIG. 3 is a right side view thereof;

FIG. 4 is a back side view thereof;

FIG. 5 is a top view thereof;

FIG. 6 is a left side view thereof; and,

FIG. 7 is a bottom view thereof.

The broken lines shown in FIGS. 1, 2, 4 and 7 represent portions of the article that are not included in the claimed design.
